Lester Sargent

Attorney

UNITED STATES PATENT OFFICE.

DENNIS L. NEWTON, OF FORT MADISON, IOWA.

BANDAGE AND TOURNIQUET.

Application filed December 21, 1925. Serial No. 76,910.

The object of my invention is to provide a novel bandage or tourniquet which can be conveniently and efficiently applied and readily fastened in place; to provide a device of this character which can be easily removed by the patient if so desired, and which has a novel combination and arrangement of parts as hereinafter disclosed. I attain these and other objects of the invention by 10 the device illustrated in the accompanying drawings, in which—

Figure 1 is a perspective view of the device in use;

Fig. 2 is a plan view of one form of my invention;

Fig. 3 is a similar view of another form of the invention;

Fig. 4 is a detail longitudinal sectional view of my preferred form of fastening device; and

Fig. 5 is a perspective view of my preferred form of fastening device.

Like numerals indicate like parts in each of the several views.

Referring to the accompanying drawings, I provide an elastic or resilient band 1, preferably covered at one end by a strip of tape 2 or other suitable material. In the alternative form of my invention illustrated in Fig. 3, I provide a flexible cloth or similar covering 7, of suitable length to loosely cover the band when stretched, and in this form of my invention, the tape 2 may be omitted.

Attached to one end of the band I provide a suitable button 3. I also provide a suitable fastening device positioned just beyond the button near the end of the band and which may consist either of the elongated wire member 4 and wire tongue 5, as shown in Figs. 2, 3 and 4, or a plate member 8, corresponding in function with wire loop 4 and having a tongue 10 corresponding in function with the wire tongue 5 shown in Figs. 2, 3 and 4. I provide suitable tape or cord attached to the wire loop 4 of Figs. 2, 3 and 4, or to the plate 8 through aperture 9, as shown in Fig. 5.

The device is applied like a bandage, by stretching the rubber band 1 and then by passing it around the arm (or leg), at the same time keeping it stretched, thus constricting or stopping the circulation of blood without pain or discomfort or injury to the blood vessels. When sufficient constriction is had, the attached tape 6 is carried on

around the arm and given two or three turns around the button 3, as shown in Figure 1, thus holding the bandage firmly in place until it is desired to remove it, which is easily done by removing the tape from 60 around the button. The elasticity in the rubber band 1 usually causes the bandage to release itself. Its easy application by the physician or attendant and its easy removal by the patient, leaving the physician's hands 65 sterile and free to continue with an operation without fear of contamination by handling the device after having been applied makes it especially advantageous. The device is light, simple and inexpensive but positive in its 70 action and adapts itself to any size arm, finger, or leg. When applied, it remains firm until released. Its instant release does not disturb the needle in the vein while an intravenous operation is in progress. It controls 75 hemorrhages in emergencies wherever it can be applied. The means of fastening it in place is convenient and prevents unwinding of the tape.

The device is especially adapted for intravenous medication.

In the following claims, the expression "cord" shall be construed to apply to the member 6, whether said member be a cord or a narrow strip of tape; and the phrase "fastening device" shall be construed to apply to either of the fastening devices described in the foregoing specification, or a substantially similar device.

What I claim is:

1. A bandage or tourniquet comprising a rubber band, a flexible cloth or similar cover loosely enclosing the band, a fastening device affixed to one end of the band, a cord affixed to said fastening device, and means for anchoring the cord to the fastening device when the bandage is in place.

2. In a bandage or tourniquet, the combination of a resilient band, a flexible cloth or similar cover loosely mounted on said band to permit of stretching of the band, a fastening device secured to one end of the band, a cord secured to the fastening device, said fastening device including a button around which the cord is to be wound when the bandage is in place, the loose end of the cord to be drawn under fastening device to prevent the cord from unwinding from around the button.

DENNIS L. NEWTON.
